UNITED STATES PATENT OFFICE.

GREELEY ELSWORTH LACKEY, OF BURLINGTON, IOWA.

MATTRESS.

1,153,120.

Specification of Letters Patent.

Patented Sept. 7, 1915.

Application filed February 3, 1914. Serial No. 816,181.

To all whom it may concern:

Be it known that I, GREELEY ELSWORTH LACKEY, a citizen of the United States, and a resident of Burlington, in the county of 5 Des Moines and State of Iowa, have made certain new and useful Improvements in Mattresses, of which the following is a specification.

My invention is an improvement in mattresses, and has for its object to provide a device of the character specified, wherein the mattress is composed of a series of similar connected sections, each section being square in cross sections and having its four sides 10 of equal size, and wherein the sections are connected in such manner that all of the sides of the sections may be used.

In the drawings: Figure 1 is a perspective view of a portion of a mattress constructed 20 in accordance with the invention, Fig. 2 is an enlarged vertical section, and Figs. 3, 4 and 5 are diagrammatic views, showing the different methods of arranging the sections.

With the ordinary mattress, the arrangement 25 is such that continuous wear is brought upon the opposite faces of the mattress, and in addition to the excessive wear brought upon the covering, the filling or stuffing of the mattress tends to gather in lumps, thus 30 destroying the comfort of the mattress. In addition to the short life of the mattress because of the manner in which it is made, the mattress cannot be aired readily, because but the two surfaces of the mattress may be exposed 35 to sun light and air.

The present embodiment of the invention as shown in Fig. 1, is composed of a series 40 of independent and similar sections, each section being square in cross section and having four of its sides of equal area, and the sections are so connected, that all of the four sides of the sections may be brought into use.

As shown in Fig. 1, the sections 1 of the 45 mattress have a covering 2 of fabric material, and a stuffing 3 of any suitable material, as for instance hair, cotton, felt, straw, excelsior or the like.

The complete mattresses may be of any 50 desired size, and the sections may be of a length corresponding to the length of the mattress desired, that is the long axis of the sections may extend longitudinally of the mattress, or the sections may be of a length

corresponding to the width of the mattress 55 desired, and be arranged transversely of the mattress.

In making the mattress, the sections are arranged alongside each other, as shown in Figs. 1 and 2, and each section is connected 60 to the succeeding section throughout the length of one corner of the said section, as shown at 4, the connection being made in any suitable manner.

As shown more particularly in Fig. 2, the 65 first and second sections are connected at their lower corners, while the second and third sections are connected at their upper corners.

The connections 4 are hinged connections, 70 so that the sections may swing freely with respect to each other, and when the sections are laid alongside each other, as shown in Fig. 1, the alternate hinge connections will be at the under side of the mattress, while 75 the intermediate hinge connections will be at the upper side of the mattress.

As before stated, the four sides of each section are of equal size, and of the same size as the four sides of every other section, and 80 by properly manipulating the sections the several sides of the sections may be brought upward, so that the wear throughout the covering and the mattress will be uniform, and so that the tendency of the stuffing or 85 filling of the sections to ball up will be eliminated.

Referring to Figs. 3, 4 and 5, wherein the sections of the mattress from right to left are designated by the reference characters 90 A, B, C, D, E and F, it will be seen that by partially turning the sections A and B on their long axis in opposite directions, the hinge connections 4 between the sections which in Fig. 2 are downward are moved 95 upward, as shown in Fig. 4, until the said hinge connections are at the upper surface of the mattress, as shown in Fig. 5.

The hinge connection between the sections B and C which was at the upper side of the 100 mattress is brought to the under side, by swinging the sections B and C in opposite directions. In like manner the hinge connection between the sections C and D and the hinge connection between the sections 105 E and F are brought upward, that is to the upper side of the mattress, while the hinge connection between the sections D and E is

brought to the under side of the mattress. This arrangement completed is shown in Fig. 5.

By so moving the sections, that portion of the covering of the sections which in Fig. 2 is between the adjacent sections, and thus but little exposed to wear is now the upper surface of the mattress, and the former upper surface is now between the sections. By 10 reversing the mattress as a whole, that is by moving the mattress so that the upper surface shown in Fig. 2 is the under surface, the other two sides of each section may be brought into position for use.

15 When airing the mattress, it may be reversed and handled in precisely the same manner as above described, to bring all of the sides of the several sections upward, to receive the beneficial effect of sun and air. 20 With the improved form of mattress, dust cannot collect, nor can the filling of the sections become knotted and collected into lumps.

With the ordinary mattress, and with a 25 single occupant the filling of the mattress tends to move away from the central portion thereof toward the sides, so that the mattress soon loses its shape and becomes uncomfortable for the user. With the present 30 construction the relative arrangement of the sections may be changed whenever desired, so that the mattress as a whole is never subjected for long at a time to any one position of the user.

35 The improved mattress is in effect so far as concerns the covering two mattresses, since there are four surfaces any two of which may be brought into position to receive the wear. The cross section of the 40 sections will of course depend upon the thickness of the mattress desired, and the length of the sections will depend upon the width or the length of the mattress being constructed.

45 Preferably a felt mattress will be composed of two or three portions, each portion

consisting of a series of sections connected as shown. As for instance, a mattress may be composed of fifteen sections, and of the fifteen sections there will be three lots or 50 portions of five sections each. The five sections of each portion will be connected, as shown in Figs. 1 and 2. This arrangement is for convenience, since it will permit the easy handling of the mattress as a whole, 55 and will permit the mattress to be packed in a compact and small package.

In addition, by dividing the mattress into units and connecting the units in several series, a delicate woman can manipulate the 60 single portions or sections of units without help, either to change the wearing surface or to transport the portions or sections of units from place to place. Any one or all of the sections or portions may thus be exposed to the air, and without any particular 65 exertion of strength.

In practice, when the mattress is formed from more than one section, the sections 70 may be interchanged, to provide for uniform wear, or either section may be replaced by a new one. The mattress may be tufted, tied or quilted, to prevent shifting or matting of the filling.

I claim:

75 A mattress section consisting of a series of connected units, the units being similar in shape and size, each unit having four equal sides, and the units of each section being arranged alongside each other and connected together by a hinge connection, the alternate hinge connections being at the upper side of the mattress, and the intermediate hinge connections being at the lower side of the mattress for the purpose specified, 80 each unit consisting of a separate body and end covering and a filling.

85 GREELEY ELSWORTH LACKEY.
